1

This invention relates to the dividing or separation of a warp stop motion blade from a series of blades.

In order to divide or separate a blade from a series of warp stop motion blades, constructions including relatively small permanent magnets or suction heads are known for separating the foremost blade in a row. Devices of this type however have the drawback that a single blade is not divided and separated from the series with sufficient reliability. For example, it frequently happens that blades which may be greasy or which adhere to one another for any other reason are carried along with the foremost blade when such blade is separated. Also in constructions wherein in suction action is utilized only the blades which present to the suction head a plane and relatively large engagement area may be used so that a relatively expensive construction is required for developing the requisite vacuum. It is an object of the invention to provide a construction avoiding the above disadvantages.

Furthermore in using dividing devices having permanent magnets of slight strength there is the risk that the blades upon being separated will leave such magnets and when stronger magnets are used the blades being separated may carry along with them one or more of the immediately following blades in the series. This latter contingency is particularly true if the blades are very thin. Furthermore it may also happen that the blades which follow the blade to be separated or divided off may first be removed and then drop off or trail behind so that the distance between the separated blade and the following blade is reduced to such an extent that the drawing-in of a warp thread is rendered most difficult. It is a further object to avoid the above disadvantages.

A further object of the invention is to provide a construction wherein the dividing or separating member cooperates with a knife in such a way that the knife edge engages with the blades in the series immediately behind the blade separated.

A still further object is to provide a construction wherein a magnet of sufficient strength may be used to ensure the separation of one blade from the series without fail. If therefore two or more blades are liable to be removed because of the excessive attractive force of the magnet the superfluous blades are prevented from being carried along with the dividing or separating member by the knife. The invention therefore is particularly well suited for removing blades from a

2

single series of blades as well as from any desired number of series.

A still further object of the invention is to provide means whereby the distance between the dividing member and the knife may be varied so as to be adjusted in accordance with the thickness of a blade.

A still further object of the invention is to provide a construction which is not only suitable for dividing devices employing magnets but also for any other blade removing means such as, for example, suction heads.

With the above and other objects in view which will become apparent from the detailed description below, the invention is illustrated in the drawings by way of example only, in which:

Fig. 1 is a front view of the dividing or separating device with parts in cross-section;

Fig. 2 is a side elevational view of the construction shown in Fig. 1;

Fig. 3 is a top plan view of the construction shown in Fig. 1;

Fig. 4 is a side view of a detail of a control device;

Fig. 5 is a side elevational view showing a blade held in the drawing in position by a magnet;

Fig. 6 is a similar view showing the magnet in a terminal position; and

Fig. 7 is a diagram showing operation during a complete cycle.

In the present instance four parallel carrier bars 1 are shown supported by the frame of the machine in fixed position and flat warp stop motion blades 2 are mounted on the bars by the slots provided therein.

The dividing or separation of the foremost blade of each series of blades is effected by a permanent magnet 3 associated with each row of blades. Each magnet is secured to a supporting body 4 with the magnet poles thereof located at the left and right hand side respectively of the associated carrier bar 1. In the position where the blade is gripped the poles of each magnet extend, as shown in Fig. 2, below the upper edge of the carrier bar 1.

All of the supporting bodies 4 are connected with one another by a stirrup 6 to which each body is individually secured and the stirrup 6 is rotatably mounted upon a shaft 5 which is supported in a mounting shield 24. With each carrier bar 1 and therefore with each series of blades there is provided a two-armed lever 7 which is secured by a bolt 8 to a mounting 9 which is rotatably mounted on the shaft 5 so that the lever 7 may oscillate in two planes at right angles to

one another. The arm of each lever 7 extending towards the blades 2 is provided with a knife 10 which terminates, as shown in Fig. 1, in an edge 10' which may be projected laterally to cooperate with the respective carrier bar 1. A tension spring 11 engages with the other arm of each lever 7 and the tensile force of the spring 11 comprises a longitudinal component and a component transversely of the carrier bar 1.

A cylindrical bolt 1' is provided on the upper end of the lever 7 for engaging the circumference of a pusher or plunger 12 having a conical surface portion 12' and a disc 12''. The four plungers 12 are axially displaceably mounted in a common U-shaped carrier 13 and are each urged by a spring 14 against a control drum 15 for common control by means of the four cams 15' on the control drum 15 which are spaced from one another by 90°. The control drum 15 is driven as shown in Fig. 4 by a ratchet wheel 16 operated by a pawl 17 which is mounted on a rocker 18 which in turn is rotatably mounted on a shaft 19.

A crank 20 through a connecting rod 21 transmits a reciprocating movement to the rocker 18 which is pivoted to the rod 21. A connecting rod 22 is also pivotally connected to the crank 20 and the rod 22 is pivotally connected by a bolt 23 to a link 25 which in turn is connected with the supporting body 4 which is adjacent the mounting shield 24. A control plate 28, urged by a tension spring 27, is mounted upon an axle 26 rotatably mounted on the mounting shield 24. A pin 29 secured to the link 25 engages in a cam groove 28' provided in the control plate 28.

On the rotatable axle 26 four ejecting levers 30 are fixed each of which is associated with a magnet 3 and consequently also with the respective carrier bar 1 and is arranged for swinging movement between the two magnet poles concerned.

The operation of the dividing device is as follows:

The crank 20 is rotated by means of a driving motor (not shown), which can be cut in and cut out by means of a floor contact or may be connected with a power-take-off, as shown in the patent to Moore, No. 1,259,546. The rotation in clockwise direction starts from the position shown in Fig. 5. The function of the apparatus is, however, easier to explain, if one starts with the position shown in Fig. 2, at which time the crank 20 is in rotation.

By the action of the intermittently fed rotatable crank 20 the four supporting bodies 4 together with the associated magnets 3 through the connecting rod 22 and the link 25 have a swinging movement imparted thereto. By this means the bodies are moved during a complete revolution of the crank through 360° from the blade-gripping position as shown in Fig. 2 into the drawing-in position shown in Fig. 5; into the terminal position shown in Fig. 6 and then back again into the blade-gripping position shown in Fig. 2. The device is temporarily halted by the operator (Fig. 5) while a thread is threaded through a blade 2.

If the dividing device is used without drawing in the thread through the blades as for dividing the blades for the purpose of donning the blades on the warp threads the drive for the dividing device may operate continuously without any intermission.

The pawl 17 carried by the rocker 18 is swung by the connecting rod 21 which is reciprocated by the crank 20 so that the ratchet wheel 16 on the

control drum 15 is rotated each time through 90° for one complete revolution of the crank. In this way one of the four cams 15' on the control drum 15 moves a plunger 12 associated with such cam to shift such plunger axially against the action of its associated spring 14. The associated lever 7 is then pivoted about its bolt 8 due to the cooperation of the conical surface portion 12' of the plunger 12 and the knife edge 10' of the associated knife 10 is moved from the range of travel of the blades so that the knife as shown in Fig. 1 at the left hand side is clear of the series *a* of the blades 2. The knives, which pertain to the series *a*, *a*₂ and *a*₃ remain, however, in position so that they prevent any removal of the plates in such series by the associated magnets.

During the movement of the plunger 12 and the knife carrier lever 7 the four supporting bodies 4 as well as the magnets 3 associated therewith will have been rotated by the action of the stirrup 6 into the blade gripping position as shown in Fig. 2. The poles of the magnets 3 located at both sides of a carrier bar 1 then contact the leading blade of the respective series in this case the series *a* to move it upon subsequent movement of the supporting bodies 4 from the position shown in Fig. 2 to the drawing-in position shown in Fig. 5. The knives associated with the other series prevent, as stated above, the foremost plates from being dragged along by the magnet.

During this movement of the supporting body 4 the cylindrical bolt 1' of the lever 7 slides along a generatrix of the conical surface portion 12' of the associated plunger 12 under the influence of the spring 11. During this movement the knife 10 which may be adjusted by a screw 31 on the magnet 3 to a spacing therefrom equalling a blade thickness, swings laterally and so inserts itself in the space between the foremost and the following blade thereby restraining the remaining blades 2 of series *a* and preventing such blades from being carried along by the magnets 3. When the cylindrical bolt 1' of the lever 7 strikes the end face of the disc 12'' facing the conical surface portion 12' of the plunger 12 the movement of the knife carrier lever 7 is stopped while the supporting bodies 4 continue in their movement to the drawing-in position of Fig. 5.

In this way any blades 2 that may adhere to the blade 2 which is being divided off are reliably retained and a sufficient spacing between such blade being divided off and the series of blades is secured so as to provide a more convenient drawing-in of a thread through the blade 2 divided off. The blade 2 which has thus been divided off maintains an oblique position which can be secured by correspondingly obliquely arranged bearing surfaces on the poles of the magnets 3.

The four ejecting levers 30 which are disposed on the axle 26, so that they rotate uniformly, follow the movement of the supporting bodies 4 and of the magnets 3, so that that ejector which belongs to that pair of magnets which has separated a blade contacts this blade and forces it, as shown in Fig. 5, against the inclined surfaces of the two magnets. In this manner an eventual falling-off of the blades which are separated and hang on the magnets 3 is prevented. The movement of the ejecting levers 30 is effected by means of the cam groove 28' in the control plate 28. This control plate 28 is fastened on the axle 26, and is secured to the outermost supporting body 4. The cam groove is so developed that the ejecting levers follow the supporting bodies and reach the

pole surfaces in the position shown in Fig. 5, as described above. Under the influence of the spring 27, the ejecting levers 30 have the tendency to pass between the two magnets pertaining to one carrier bar and swing further toward the left (Figs. 5 and 6).

When the thread is drawn in, the operator sets the crank again in motion, whereby the magnets continue towards the left, until they arrive in the final position shown in Fig. 6, while the ejecting levers 30 follow them. The ejector lever, which has engaged a blade, shoves the same during its progress into the position shown in Fig. 6 downwardly on the poles of the magnets. At the last moment the ejector strikes the blade under the influence of the spring 27 so that it is moved a little further along the bar 1. When the crank is rotated further, the connecting rod 22 moves the magnets back again into the position shown in Fig. 2.

While the supporting bodies 4 move from the position shown in Fig. 6 to the position shown in Fig. 2 the ejecting levers 30 also pivot back into their initial position as shown in Fig. 2. In the course of the next following revolution of the crank 20 the ratchet wheel 16 of the control drum 15 is rotated 90° by the pawl 17 and another cam 15' will strike the plunger 12 associated therewith whereupon the cycle of operations begins anew and the process is repeated in the same way for the series *a*1.

From the preceding explanation it follows that the knife of a knife carrier lever always enters between the dividing member and the foremost blade of that series of blades from which the foremost blade is not to be divided. A variation in the sequence of operating the plungers 12 may be obtained by interchanging the control drum 15.

The cooperative movement of the various elements is diagrammatically illustrated in the diagram of Fig. 7 which gives a complete cycle of 360° of the crank 20. The various elements are indicated along the ordinate while the time of movement with relation to the movement of the crank is shown on the abscissa. The stationary period for the crank 20 during which the drawing-in operation takes place is indicated by dotted lines.

The start of the movements at 0 degrees corresponds with the position shown in Figs. 1, 2, and 3. The crank rotates from this position in clockwise direction through an angle of more than 90 degrees during which the magnets move away from the series of blades, and the magnets of the series *a* take along a blade, while the other three series are retained by the knives. As can be seen from the diagram for the knife pertaining to series *a*, it is swung in back of the blade when the magnets have first moved a slight portion of their way. The insertion of the knife starts at approximately 20 degrees and is finished at about 50 degrees. The movement of the ejectors follows the movement of the magnets so that the ejector pertaining to the series *a* starts at about 95 degrees to press on the blade lying on the inclined surfaces of the magnet.

The apparatus reaches the drawing-in position at about 105 degrees and is maintained in this position as long as the operator desires. When the rotation of the crank is resumed, the crank now travels without stopping through the positions from 105 degrees to 360 degrees, and again from 0 degrees to 105 degrees.

During this period the magnets move towards the left as seen in Fig. 2 until the crank has

passed 180 degrees. During this time the ejectors move along also and shove the blade downwardly along the inclined surfaces of the magnets. Upon continued rotation of the crank, the magnets return towards the right and at 360 degrees they are back again at the position shown in Fig. 2.

The control drum 15 is stationary at 0 degrees, at the start of the rotation of the crank, since the connecting rod 21 moves downwardly between 10 0 degrees and about 125 degrees. After 125 degrees are passed, the rod 21 moves upwardly and actuates the pawl 17 causing the ratchet wheel 16 to rotate 90 degrees. The movement of the pawl is finished at about 305 degrees. The control drum 15 and also the cams 15' therefore are stationary from 305 degrees to 360 degrees and from 0 degrees to 125 degrees of the rotation of the crank. The same holds for the plungers 12, the movement of which is caused by the cams 15'.

It is thought that the invention and its advantages will be understood from the foregoing description and it is apparent that various changes may be made in the form, construction and arrangement of the parts without departing from the spirit and scope of the invention or sacrificing its material advantages, the form hereinbefore described and illustrated in the drawings being merely a preferred embodiment thereof.

I claim:

1. In a device for dividing warp stop motion blades from a series of blades, the combination with a row of warp stop motion blades constituting the series of blades, a support extending 35 in the direction of said blade row for sustaining said row for the individual blades to be removable in said direction, dividing means for exerting attractive removing power on the foremost blade in said row, of a knife having a knife edge for cooperation with said dividing means, and screw means for adjusting the distance between said dividing means and said knife commensurate with the thickness of said blades, said knife edge cooperating with said dividing means by interengagement with said series of blades at said distance behind said foremost blade in said series.

2. In a device for dividing warp stop motion blades from various series of blades in the course of successive working cycles, the combination with each individual row of blades constituting 50 said various series, a support extending in the direction of said blade row for sustaining said row for the individual blades to be removable in said direction, dividing means for exerting attractive removing power on the foremost blade in said row, of a knife for each said row having a knife edge, displaceable plungers for controlling said knives, a roll for controlling said plungers, for said knife edge to cooperate with the respective said dividing means by interengagement of 55 said knife edge with the associated series of blades directly behind said foremost blade in each series of blades from which said foremost blade is to be divided off, and means for shifting said 60 knife edge in each row from which said foremost blade is not to be divided off between said dividing means and said foremost blade.

3. In a device for dividing warp stop motion blades from a series of blades, the combination with a row of warp stop motion blades constituting 70 the series of blades, of a support extending in the direction of said blade row for sustaining said row for the individual blades to be removed in said direction, dividing means for exerting attractive removing power on the foremost blade in

said row, a knife having a knife edge cooperating with said dividing means and a cam operated plunger cooperating with said knife for engaging said knife edge with said series directly behind said foremost blade in said series to be divided off shortly after said foremost blade has been removed by said dividing means from said series.

4. In a device for dividing warp stop motion blades from a series of blades, the combination with a row of warp stop motion blades constituting a series of blades, of a support extending in the direction of said blade row for sustaining said row for the individual blades to be removable in said direction, permanent magnetic means for attracting the foremost blade in said row, a knife having a knife edge for cooperation with said magnetic means and means cooperating with said knife for engaging said knife edge with said series directly behind said foremost blade in said series to be divided off immediately after a slight movement of said foremost blade from said series by said magnetic means.

5. In a device for dividing warp stop motion blades from a series of blades, the combination with a row of warp stop motion blades constituting the series of blades, of a support extending in the direction of said blade row for sustaining said row for the individual blades to be removable in said direction, dividing means for exerting attractive removing power on the foremost blade in said row, means for moving said dividing means together with said attracted foremost blade away from said row, a knife having a knife edge cooperating with said dividing means by interengagement of said knife edge with said series directly behind said foremost blade in said series blade row, and means for setting said knife at rest with said knife edge in said position of interengagement, while said dividing means moves said foremost blade away from said row by actuation of said moving means.

6. In a device for dividing a warp stop motion blade from a row of blades in a series of rows of blades the combination comprising supports extending in the direction of each blade row for sustaining said row for the individual blades to be removable in said direction, dividing means

for each row for exerting attractive removing power on the foremost blade in each row, means for moving said dividing means together with said attracted foremost blade away from said row, a knife having a knife edge for each row for cooperating with said dividing means, means for operating the knife in the row from which a blade is to be divided to retain the blades behind the foremost blade after a slight movement of said foremost blade by said dividing means and means for operating the knives in the other rows to retain all the blades therein and prevent action of said dividing means on the blades in said last named rows.

5. In a device for dividing warp stop motion blades from a series of blades, the combination with a row of warp stop motion blades constituting the series of blades, of a support extending in the direction of said blade row for sustaining said row for the individual blades to be removed in said direction, dividing means for exerting attractive removing power on the foremost blade in said row, a knife having a knife edge cooperating with said dividing means and a cam operated mechanism cooperating with said knife for removing said knife from in front of the foremost blade in said series and inserting said knife directly behind said foremost blade in said series shortly after said foremost blade has been slightly removed by said dividing means from said series.
